UNITED STATES PATENT OFFICE.

YUSUKE TAMAMURA, OF TOKYO-FU, JAPAN.

DIFFERENTIAL CLIP FOR AERIAL ROPEWAYS.

1,392,978.

Specification of Letters Patent. Patented Oct. 11, 1921.

Application filed February 14, 1921. Serial No. 444,920.

To all whom it may concern:

Be it known that I, YUSUKE TAMAMURA, civil engineer, a subject of His Majesty the Emperor of Japan, residing at No. 18 5 Genbei, Totsuka - machi, Toyotama - gun, Tokyo-fu, Japan, have invented certain new and useful Improvements in Differential Clips for Aerial Ropeways, of which the following is a specification.

10 In the specification of my United States Letters Patent No. 850,504 granted April 16, 1907, there is described a clip or grip for engaging the hauling-rope in aerial ropeways wherein use is made of two jaw-levers 15 of unequal lengths which are operated by gravity through the weight of the car or the car and its contents.

This invention relates to a clip or grip of the same general construction as the one described in the aforementioned patent but 20 provides a more improved apparatus which fulfills more effectively the purpose for which the apparatus is designed.

According to this invention the free ends 25 of the longer lever-arms are adjustably fixed to the frame member at a point which is normally lower than the hauling-rope, and on the tail portion of the shorter lever-arm is provided an arcuate slot along which a 30 pin is made to slide longitudinally as the inclination of the hauling-rope varies, which sliding will have the effect of automatically adjusting the effective length of the shorter lever-arm. The longitudinal motion of the 35 said pin is caused by means of another pin rigidly connected with the said first pin and an inclined slot provided on an annular member connected in driving relation to the carriage hanger. The invention further 40 comprises means of magnifying angle of rotation, such as a set of toothed wheels of different diameters, by which the rotation of the hanger relative to the system of the lever-arms caused by the varying inclinations 45 of the hauling-rope may be magnified in proportion to the ratio of the diameters of the said toothed wheels. This magnification of angular displacement will make the sliding motion of the second pin along 50 the inclined slot smoother.

The object of the present invention is to provide a grip which will firmly grasp the hauling-rope in an inclined position in such a manner that the grasping force, instead 55 of being constant as in grips heretofore employed, will be increased as the inclination

of the hauling-rope increases, thus obviating the slightest possibility of slipping.

Another object of the invention is to provide a grip which may be adapted to any 60 system of cable transportation, either single or double, regardless of the amount of the load to be carried.

Still another object is to so construct a grip that it will effectively and reliably 65 operate both at the starting and at the arriving stations. The foregoing objects are accomplished by means of the structure and the relative arrangement of parts as are illustrated in the following specification and 70 described in the claims.

On the drawings, similar characters of reference indicate corresponding parts in the several views.

Figure 1 is a vertical sectional view of my 75 improved grip in operating position, the section being taken on the central line of Fig. 2.

Fig. 2 is a top plan view.

Fig. 3 is a front view of my improved 80 grip in the starting position at a loading station.

Fig. 4 is a side view of my grip in a released position.

Fig. 5 is an enlarged detail view of the 85 cam-ring.

Fig. 6 is an enlarged sectional view showing a double-spring-holding means for grip-wheel system.

Figs. 7 and 8 are modifications applicable 90 to a double-rope system.

Referring now more particularly to the reference numbers on the drawings, the longer lever-arms 2 and the shorter lever-arms 3 are pivotally connected by the pivot-bolt 6. The lever-arms 2 and 3 extend to common gripping jaws 4 and 5 respectively which cooperate in firmly grasping the hauling-rope 1. An arcuate slot 7 is formed on the tail portion of the shorter lever-arm 3, 100 along which slides a horizontal pin 8 as the inclination of the hauling-rope 1 varies. Pin 8 is rigidly fixed to the extensions 9' which are integral with the annular member 9 turnably mounted upon the cam-ring 105 10. To the annular member 9 is fixed a radial pin 11 which coöperating with the inclined slot 12 formed on the cam-ring 10 causes the horizontal pin 8 to slide along the arcuate slot 7. The inclined slot 12 is 110 sloped from the apex of the cam-ring in the same direction both ways so that when the

hauling-rope is in a horizontal position the radial pin 11 and consequently the horizontal pin 8 will be situated nearest to the pivot-bolt 6. In this position, the radial 5 pin 11 is at the vertex of the slot 12.

From this point the slot 12 slopes backward on both sides of the cam-ring 10 as is shown in Fig. 5. By rotation of the cam-ring 10 caused by the relative rotation of 10 the hanger 18 with respect to the system of lever-arms as hereinafter more fully described, the radial pin 11 and consequently the horizontal pin 8 will travel to the right, which makes in effect the length of the 15 shorter arm 3 longer, and which necessarily increases the force of compression of the gripping jaws. When the hauling-rope resumes a horizontal position, the pins come back to the original extreme position which 20 is nearest to the pivot-bolt 6.

On one side of the cam-ring 10 is provided integral with it a pinion 13. The cam-ring together with the pinion 13 is rotatably mounted upon the small shaft 14' 25 which is an eccentric extension of the main shaft 14. The pinion 13 engages internally with the toothed ring 15 which is formed at one end of the sleeve member 16. The sleeve member 16 is rigidly fixed to the 30 hanger 18 by means of a key 17. In this way the rotating motion of the hanger is transmitted to the toothed ring 15.

The rear ends of the longer lever-arms 2 are pivotally connected to a sleeve member 35 20, which is adjustably connected to another sleeve member 21 upon its screw-threaded extension 21', which in turn is keyed to the main shaft 14. By this construction the 40 axis of rotation of the pinion and cam-ring is placed on a fixed relative position with respect to the system of lever-arms.

In case the hauling-rope is horizontal the parts assume the relative positions shown in Fig. 1. When the hauling rope becomes 45 inclined, the hanger, because of the weight which it carries, will rotate relatively to the system of lever-arms and the main shaft connected thereto. The sleeve member 16 together with the toothed ring 15, being 50 keyed to the hanger 18 at its hub portion, will rotate and cause the pinion 13 and the cam-ring 10 to rotate. The diameter of the pinion 13 being of a lesser dimension than that of the toothed ring 15, the angle of 55 rotation of the cam-ring will thereby be magnified in an inverse ratio of the diameters. That is to say, if the diameters are in the ratio of two to three, an inclination of the hauling-rope equal to sixty degrees 60 will cause a rotation of the cam-ring of ninety degrees which makes the radial pin 11 travel a distance along the inclined slot 12 corresponding to a quarter length of the periphery of the cam-ring.

65 In aerial ropeways, it can safely be said

that the inclination of the hauling-rope never exceeds sixty degrees. It is, therefore, sufficient to provide the inclined slot 12 for the quarter length of the periphery on both sides of cam-ring 10. But to allow 70 for the swinging motions of the hanger, by which angular displacement of the hanger may eventually overshoot the aforementioned limit I provide a short extension, say of forty-five degrees, extending straight 75 downward on each extremity of the slot. This allows a relative maximum angular displacement of ninety degrees of the hanger from the position it will occupy 80 when the hauling rope is in a horizontal position.

In Figs. 7 and 8 is shown a modification of my improved grip designed to be used in a double-rope-way system, in which the carriage wheels 23 which are adapted to roll 85 along the track-rope 35 and which are provided on the system of carriage hinged on the pivot-bolt 6 are situated right above the said pivot-bolt. The rocking box 32 which is rotatably mounted on the wheel carriage is 90 hinged by means of a pair of supporting bars 30 on the pivot-bolt 6. The weight of the car together with its contents is supported partly by the track-rope and partly by the hauling-rope. On arriving at a station small wheels 23 mounted on an upward extension of the arm 22 are raised by a pair of uncoupling rails 27, whereby the gravitational force acting on the hanger 18 is transmitted, without passing through the lever-arms 2 and 3, directly to the said small 95 wheels and the uncoupling rails 27. A slider 31 is provided at the central portion of the rocking box 32. The shaft 24 on which the wheels 23 as well as the slider 31 are mounted slides vertically up and down along the aperture formed in the rocking box 32. The action of the slider 31 is to maintain the wheel carriage always in an upright position. 100

The grip shown in Figs. 7 and 8 is, of course, of the same general construction as that of Fig. 1, with the difference that besides being upside-down the jaw 4 of the longer lever-arms 2 is formed on the inside 115 and the jaw 5 of the shorter lever-arms 3 on the outside of the hauling-rope 1. Both, however, operate similarly in that the gripping-jaws engage or disengage the hauling-rope as the pivot-bolt 6 comes down or 120 comes up.

In the single-rope-way system the carriage wheels 23 traveling on the suspension rail 27 provided at a station correspond to a wheel running on one of the uncoupling rails in 125 the double rope-way system. These wheels being situated on one side of the car cannot be placed right above the hauling-rope 1 but must be placed at a position sufficiently removed from the hauling-rope so that they 130

will not interfere with the supporting roller 28 on the standard during the travel of the car. It is, moreover, essential that the distance between the hauling rope 1 and the 5 wheels 23 be kept constant, otherwise the gripping jaws may fail to engage the hauling-rope at starting or the wheels may derail on arriving at a station. To keep this distance substantially constant, the center of 10 the two opposing gripping jaws must always lie in one and the same vertical plane, irrespectively whether the jaws are in operative gripping position or not. To accomplish this end, the terminal shaft 19 of the longer 15 lever-arms 2 is placed far below the main shaft 14 on the same level with the center 1 of opposing jaws 4 and 5 when the same are in a fully released position as indicated in Fig. 4. In this case, the gripping jaws will 20 just assume the right position to grip the hauling-rope as soon as the car is freed from the suspension rail 27.

When the jaws are engaged with the hauling-rope and the whole weight of the car 25 falls upon it, the axial line of the sleeve member 16, to which the hanger 18 is rigidly keyed and which is at the same time the axis of rotation of the gyrating system, is arranged to pass through the center 1 of the 30 gripping jaws. By this arrangement no bending moment on the hauling-rope will be created as the hanger oscillates around the said axis.

In single-rope-way system, as is shown in 35 Fig. 4, in order to minimize the oscillating motion of the car due to the sudden change of the point of suspension at starting and arrival a pair of running wheels 23 is usually rather closely situated to the hauling-rope 1. These wheels, moreover, having between them a group of lever-arms are placed far apart from each other. It is, therefore, necessary during the travel of the car that the system comprising these wheels 23 and 40 the carriage 22 be kept substantially in parallel relation to the hauling-rope 1, and that the said system be at once brought back to the said normal position as soon as the car is freed from the uncoupling rail 27. If this 45 condition is not satisfied and if the system comprising wheels and their carriage stands vertically up it will be sure to collide with the supporting rollers, which will inevitably lead to disastrous consequences. In the devices of the kind heretofore employed, it has 50 been usual to have recourse either to providing a sufficiently wide clearance between the wheels 23 and the hauling-rope 1 or to limit the inclination of the hauling-rope at 55 the starting point of a station to a definite magnitude. Both of these methods are evidently only temporizing and, therefore, undesirable. I aim to obviate these deficiencies by fixing the system of wheels resiliently to 60 the main body of the grip. This may of

course be accomplished by any suitable means. In the preferred construction shown in the annexed figures I employ as the said resilient connection a double-spring-hinge 25 usually employed in architectural constructions, which may be located within the hollow space formed in the body of the main shaft 14 (Figs. 1 and 6). At a station the wheels 23 run along the rail 27 (Fig. 3). When the car is leaving the rail 27, the system of wheels by the resilient action of the spring device 25 will be brought back to its normal position parallel to the hauling-rope 1. In Fig. 6 the spring device 25 is shown more in detail, in which the wheel-carriage 22 is turnably mounted on the sleeve member 16 by means of a sleeve portion integral with the former. The double-spring-hinge 25 is provided in the hollow space formed in the body of the main shaft 14. Link 26 80 which is connected to one of the springs projects through the aperture formed in the said sleeve portion. The double-spring-hinge 25 by its resilient action always tries to maintain the wheel-carriage 22 at a definite position with regard to the main shaft 14, that is to say, to the system of lever-arms. Arriving at a station, the system of 85 wheels 23 by the presence of the rail 27 is compelled to ride on the rail assuming a 90 position parallel to the same against the resilient action of the spring-device. This spring-device being wholly inclosed within the hollow space formed in the shaft is 95 protected from damage.

While the invention is described herein with reference to a particular embodiment, it is not limited to the specific mechanism shown or described, since other modifications may readily be used without departing 105 from the spirit and the underlying principle of this novel improvement, or the scope of the following claims.

What I claim is:

1. In apparatus of the class described, the 110 combination of a hauling rope, a carriage, rope-gripping means connected with the carriage, means for translating the force of gravity acting through the carriage upon the gripping means to make the grip effective and means operative to vary the gripping action of the said gripping means as a function of the angle of inclination of the hauling rope.

2. In apparatus of the class described, the 115 combination with a hauling rope, a carriage, a pair of lever arms of different lengths pivotally connected at one end with the carriage, pivotally interconnected intermediate their ends and formed into gripping jaws at 120 their free ends, of means operative to vary the relative lengths of the said levers as a function of the angle of inclination of the hauling rope.

3. In an apparatus of the class described, 130

the combination with a hauling rope, a carriage and gripping means comprising two lever arms of different lengths pivoted separately to the carriage at one end and pivotally interconnected intermediate their ends, the free ends being formed into gripping jaws, of means operative to vary the effective length of one of the said levers as a function of the angle of inclination of the 10 hauling rope.

4. In apparatus of the class described, the combination with a hauling rope, a carriage and gripping means comprising two lever arms of different lengths pivoted separately 15 to the carriage at one end and pivotally interconnected intermediate their ends, the free ends being formed into gripping jaws, of means operative to vary the effective length of the shorter lever arm as a function of the angle of inclination of the 20 hauling rope.

5. In apparatus of the class described, a grip comprising two lever-arms having a common axis, their shorter ends being 25 formed into jaws and their longer ends pivotally connected to the carriage, and means whereby one of the said pivotal points is moved automatically in such a manner that the effective length of that particular lever- 30 arm may be varied as the inclination of the hauling-rope varies.

6. In apparatus of the class described, a grip comprising two lever-arms of different lengths having a common axis, their shorter 35 ends being formed into jaws and their longer ends pivotally connected to the carriage, and means whereby the pivotal point of the shorter lever-arm is moved automatically in such a manner that the effective length of 40 the said lever-arm may be varied as the inclination of the hauling-rope varies.

7. In apparatus of the class described, a grip comprising two lever-arms of different lengths having a common axis, their shorter 45 ends being formed into jaws, a main shaft to which the longer end of the longer lever-arms is pivotally connected, a hanger member turnably mounted upon the said main shaft, a cam-ring provided with an inclined 50 slot and connected with the said hanger in driving relation, and an annular member turnably mounted upon the said cam-ring, being provided with a horizontal pin slideable along an arcuate slot formed on the 55 longer end of the shorter lever-arm and provided also with a radial pin coöperating with the said inclined slot on the said cam-ring.

8. In apparatus of the class described, a 60 grip comprising two lever-arms of different lengths having a common axis, their shorter ends being formed into jaws, a main shaft to which the longer end of the longer lever-arm is pivotally connected, a hanger member 65 turnably mounted upon the said main

shaft, a cam-ring provided with an inclined slot and connected in driving relation with the said hanger, and an annular member turnably mounted upon the said cam-ring being provided with a horizontal pin slideable along an arcuate slot formed on the longer end of the shorter lever arm and provided also with a radial pin coöperating with the said inclined slot on the said cam-ring, the said driving connection between 75 the hanger member and the cam-ring comprising means of magnifying the angle of rotation of the hanger relative to the said main shaft.

9. In apparatus of the class described, a 80 grip comprising two lever-arms of different lengths having a common axis, their shorter ends being formed into jaws, a main shaft to which the longer end of the longer lever-arms is pivotally connected, a hanger member turnably mounted upon the said main shaft, a cam-ring provided with an inclined slot and connected with the said hanger in driving relation, and an annular member turnably mounted upon the said cam-ring, 85 being provided with a horizontal pin slideable along an arcuate slot formed on the longer end of the shorter lever-arm and provided also with a radial pin coöperating with the said inclined slot on the said cam-ring, the said driving connection between the hanger and the cam-ring comprising an 90 interiorly toothed ring rigidly connected to the hanger and a pinion of a lesser diameter 95 integral with the said cam-ring.

10. In apparatus of the class described, a 100 grip comprising two lever-arms of different lengths having a common axis, their shorter ends being formed into jaws, a main shaft to which the longer end of the longer lever-arm is pivotally connected, a hanger member turnably mounted upon the said main shaft, a cam-ring provided with an inclined slot and connected with the said hanger by a combination of an interiorly toothed ring 105 and a pinion meshing with it, and wheels mounted on a carriage attached to the main shaft by a resilient means, the said resilient means consisting of a double-spring hinge provided in a hollow space of the said main 110 shaft.

11. In apparatus of the class described, a 115 grip comprising two sets of lever-arms, the shorter ends of each of the said sets being formed into a common jaw coöperating in 120 gripping the hauling-rope, the longer ends of one of the said sets being longer than the longer ends of the other set, each set of the said longer ends being pivotally connected to the carriage by a common pivotal point, and means whereby one of the said pivotal points is moved automatically in such a manner that the effective length of that particular lever-arm may be varied as 125 the inclination of the hauling-rope varies. 130

12. In apparatus of the class described, a grip comprising two sets of lever-arms, the shorter ends of each of the said sets being formed into a common jaw coöperating in gripping the hauling-rope, longer ends of one of the said sets being longer than the other set, the said longer ends of the longer set being pivotally connected to a main shaft the said pivotal point being situated far below the horizontal line passing through the center of the gripping jaws when same are engaged with the said hauling-rope.
- 5 In testimony whereof, I affix my signature.

YUSUKE TAMAMURA.
